UNITED STATES PATENT OFFICE.

STANLEY L. RAU, OF NEW BRIGHTON, PENNSYLVANIA.

ATTACHMENT OF CORRUGATED SHEETS TO FRAME STRUCTURES.

1,227,666.

Specification of Letters Patent. Patented May 29, 1917.

Application filed February 17, 1915. Serial No. 3,904.

To all whom it may concern:

Be it known that I, STANLEY L. RAU, residing at New Brighton, in the county of Beaver and State of Pennsylvania, a citizen of the United States, have invented or discovered certain new and useful Improvements in Attachment of Corrugated Sheets to Frame Structures, of which improvements the following is a specification:

10 As far as actual practice is concerned, corrugated sheet metal is usually attached to its supporting members, such as roof purlins or floor beams, by clinch nails extending through the sheets and bent to engage the purlins or beams after the sheets have been laid, or by straps or clips also riveted or bolted to the sheets after they are in place. In both cases it is necessary to incur the expense of a suitable scaffolding or platform beneath the sheets to support a workman for effecting the attachments. Although the actual practice is as described, I am aware that various forms of clips have been suggested which are adapted to be attached to the supporting members before the sheets are laid, and to which the sheets may subsequently be riveted by workmen on the top of the sheets, the supporting members serving to buck-up the rivets. But such 25 clips have proven unsatisfactory; first, because of their manufacturing cost; and secondly, and the most important reason, because they do not prevent a roof from rattling during wind storms, or a roof or floor 30 from becoming displaced by wind or other forces acting in various directions.

The object of my invention is to provide a simple and inexpensive sheet attaching means for the purpose described, which may 40 be secured to the supporting members before the sheets are laid thereon, and to which the sheets may be attached solely by a workman on top of the sheets, and which will hold the sheets firmly against displacement 45 by forces acting in any direction.

In the accompanying sheet of drawings, which forms part of my specification, I have illustrated my invention as applied to metallic roofs. Figure 1 is a transverse 50 section of a portion of a roof; Fig. 2 an enlarged sectional view of a single purlin showing a sheet attached thereto; Fig. 3 a longitudinal sectional view to enlarged scale taken on the line III—III, Fig. 1; Fig. 4 55 a view similar to Fig. 2 but showing an I-

beam purlin; and Fig. 5 an enlarged view of a rivet.

In the several figures like numerals are used to designate like parts.

According to the practice of my invention, in its preferred form, I provide an attaching means or clip consisting of a strip of metal bendable to engage two flanges of a purlin or beam, such strip firmly holding a rivet on the top of the purlin, the rivet 65 being provided, at a distance from its base, with a shoulder for supporting a ridge of a corrugated sheet.

The metallic strips may be of any suitable form or construction, it being only necessary that they be bendable to engage the purlin or beam flanges, and of sufficient rigidity to withstand the dislodging forces that may in practice be subsequently applied to them. As shown herein such strips consist of a metal strap 1. The rivets which I employ preferably have their outer shank portions 2 of smaller diameter than the lower portion 3, and at the meeting planes of the two shank portions shoulders 4 are 75 formed. The shank portions 3 are preferably of such length that the distance of the shoulders 4 from the base of the rivets is substantially equal to the depth of the corrugations in the sheet to be attached to the 80 purlins, the shoulders thus affording a support for the ridges of such sheet. For holding the rivets the straps 1 are preferably provided with holes 5 of substantially the same diameter as the shank portions 3, and 85 the bases of the rivets are provided with a laterally-projecting flange 6. When the roof purlins are channels, such as illustrated in Figs. 1, 2 and 3, the holes 5 are punched through the strap at such point as to leave 90 short end 1^a to be bent around the upper flanges 7 of the channels, and longer portions 1^b to extend along the back and around the lower channel flanges 8.

In case the sheets are to be attached to I-beams, the holes may be punched at the center of the straps, which are of sufficient length to bend around the oppositely disposed flanges of the beams, as clearly shown in Fig. 4.

In laying the roofing the purlins are first provided, at proper intervals, with the clips, that is, the straps and rivets. The sheets, when in place, may rest directly on the rivet shoulders 4, or, as shown herein, soft metal 105 110

washers 9 may be placed on such shoulders. Assuming that the washers have been placed, the sheets may then be laid on the rivets and punctured to permit the shank portions 5 2 to project through them. A second lot of soft metal washers 10 may then be placed around the projecting ends of the rivets, and the rivets upset to clamp the plates between the washers and firmly against the rivet 10 ledges; and, as will be seen, the upper faces of the purlins or beams afford substantial supports for the rivets while being upset.

I claim as my invention:

1. In a metallic frame structure, the combination of flanged sheet-supporting members, elongate strips of bendable metal each engaging one of said members, and each provided with a hole, rivets having their bases abutting against said members and extending through such holes, said rivets being provided at their bases with laterally extending flanges and with transversely disposed shoulders at a distance from the bases, and corrugated metal sheets supported at 15 their ridges by said rivet shoulders and engaged by the upset outer ends of the rivets.
2. In a metallic roof construction, the combination of flanged purlins, elongate strips of bendable sheet metal each engaging two flanges of a purlin, and each provided 20 with a hole, rivets resting on the top flanges of the purlins and extending through such holes, said rivets being provided at their bases with laterally extending flanges and with transversely disposed shoulders at a 25 distance from the bases, and corrugated metal sheets supported at their ridges by said rivet shoulders and clamped by the upset outer ends of the rivets.

with a hole, rivets resting on the top flanges of the purlins and extending through such holes, said rivets being provided at their bases with laterally extending flanges and with transversely disposed shoulders at a 30 distance from the bases, and corrugated metal sheets supported at their ridges by said rivet shoulders and clamped by the upset outer ends of the rivets between pairs of soft metal washers.

3. In a metallic roof construction, the combination of flanged purlins, elongate strips of bendable metal each engaging two flanges of a purlin, and each provided with a hole, rivets resting on the top flanges of 45 the purlins and extending through such holes, said rivets being provided at their bases with laterally extending flanges and with transversely disposed shoulders at a 50 distance from the bases, and corrugated metal sheets supported at their ridges by said rivet shoulders and engaged by the upset outer ends of the rivets.

In testimony whereof I have hereunto set my hand.

STANLEY L. RAU.
